UNITED STATES PATENT OFFICE

SAMUEL STEWART, OF LEWISTON, MAINE, ASSIGNOR TO BATES MANUFACTURING COMPANY, OF LEWISTON, MAINE, A CORPORATION OF MAINE

BEDSPREAD

Application filed July 2, 1929. Serial No. 375,448.

This invention relates to bedspreads or analogous ornamental covers for beds, the object of the invention being to provide a bedspread which shall be so constructed that 5 when it is in place upon the bed, it will give the appearance of a separate pillow, sham or bolster cover.

Heretofore several methods of covering the bed and pillows or bolster have been employed. One of these methods has been to employ a separate bedspread and pillow sham. Another method has been to make a bedspread which is long enough to pass under the pillow or bolster, then be folded 10 on the top side. Neither of these methods is satisfactory, chiefly on account of the time and care required to put the spread in place and to give to the bed a neat and attractive appearance. The bedspread embodying my 15 present invention gives to the bed and pillow the appearance of a separate bedspread and sham but is made up in one piece and can be put in place on the bed in a very short time and with little or no skill or care.

20 Other objects of the invention will appear in the following description and appended claim, reference being had to the accompanying drawings forming a part of this specification wherein:

25 Fig. 1 is a perspective view of a portion of a bedstead having the bedspread of my invention in position thereupon.

Fig. 2 is a top plan view of the invention with the spread open.

30 Before explaining in detail the present invention, it is to be understood that the invention is not limited in its application to the details of construction and arrangement of parts illustrated in the accompanying drawings, since the invention is capable of other 35 embodiments and of being practised or carried out in various ways. Also it is to be understood that the phraseology or terminology employed herein is for the purpose of description and not of limitation, and it is not intended to limit the invention beyond the 40 terms of the claim hereto appended as considered in view of the prior art and the requirements thereof.

45 Referring now to the drawing, 10 repre-

sents as a whole the body portion of the bedspread of my invention and 11 the attached ornamental ruffle portion or border thereof.

Referring to Fig. 2, it will be seen that the ruffle 11 is sewed or otherwise fastened at its inner edge at 12 to the upper surface of the bedspread and that the ruffle or border is placed in position upon the spread is of substantially U-shape. The material of the bedspread body and the ruffle or border is 50 preferably the same but of course may be different if desired. The finishing strip or tape 13 may be made of material different from that of the spread and ruffle. Thus it will be seen that when the bedspread is placed in position upon the mattress and pillows or bolster as the case may be, the ruffle or border 55 11 surrounds three sides of the pillow or bolster and defines it. The pillow raises up the portion of the bedspread lying inside the ruffle and the ruffle slopes downwardly and falls over the edge of the bed, so that the 60 whole has the appearance of a pillow covered by a sham and can hardly be distinguished from it. The bed can be made up by throwing the spread over the properly positioned pillow and then pulling the edges smooth. This takes but an instant and the bed is 65 given a most attractive appearance. The size 70 of the ruffle or ornamental portion 11 may be varied in size for beds of varying widths.

75 I claim:

80 A bedspread comprising a body portion adapted to cover a mattress and pillow when the latter is in usual position at the head of the bed, and a ruffle attached to the body portion near the top edge thereof and arranged in a three-sided figure having one of its sides parallel with the bottom edge of the spread, the other two sides being parallel with the side edges of the spread, thereby leaving the 85 top edge of the spread free, said ruffle forming a figure substantially defining the outline 90 of the pillow and having the appearance of a separate cover therefor.

95 In testimony whereof I affix my signature.

SAMUEL STEWART.
